W. CATLIN.
SANITARY MILK PAIL.
APPLICATION FILED APR. 3, 1917.

1,268,792.

Patented June 4, 1918.

UNITED STATES PATENT OFFICE.

WINFIELD CATLIN, OF ROCKVILLE, INDIANA, ASSIGNOR OF ONE-HALF TO THOMAS S. CATLIN, OF GUION, INDIANA.

SANITARY MILK-PAIL.

1,268,792.

Specification of Letters Patent.

Patented June 4, 1918.

Application filed April 3, 1917. Serial No. 159,386.

To all whom it may concern:

Be it known that I, WINFIELD CATLIN, a citizen of the United States, residing at Rockville, in the county of Parke and State of Indiana, have invented certain new and useful Improvements in Sanitary Milk-Pails; and I do hereby declare the following to be a full, clear, and exact description of the invention, such as will enable others skilled in the art to which it appertains to make and use the same.

The present invention relates to receptacles, and more particularly to that type adapted for containing liquid.

An object is to provide means for attachment to a receptacle to prevent the spilling of the contents thereof, when the receptacle is tilted or overturned, such as when knocked over, and to prevent the entrance of foreign matter into the receptacle.

Another object is to provide a sanitary device which may be easily and economically manufactured independently of the receptacle, and applied thereto, and to provide novel means for detachably holding the device to the receptacle.

Various other objects and advantages of this invention will be in part described, and in part understood from the following detailed description of the present preferred embodiment, the same being illustrated in the accompanying drawing, wherein,

Figure 1 is a vertical section taken substantially centrally through a receptacle, and through an attachment constructed according to this invention applied thereto.

Fig. 2 is a top plan view of the same.

Fig. 3 is a fragmentary, enlarged side elevation of the valve of the attachment and its operating mechanism, partly in section.

Fig. 4 is a fragmentary, enlarged side elevation of the upper end of the receptacle with the attachment applied thereto, showing the ear for supporting the bail and the device of this invention.

Fig. 5 is an enlarged, transverse section taken on the line 5—5 of Fig. 3, through the valve and its operating mechanism.

Referring to the drawing, A designates a container or receptacle, which may be formed in the usual manner of sheet metal, and which has at its upper margin the usual reinforcing bead B.

The device of this invention comprises a two-part body formed of a top portion 10,

and a bottom or funnel portion 11. The top portion 10 may be of concavo-convex form, may be made from sheet metal or the like, and has at its outer marginal portion an outwardly crimped supporting flange 10^a adapted to rest upon the bead B of the receptacle to support the attachment thereon. The lower edge of the top part 10 extends downwardly from the base of the flange 12 to form an attaching rim 13.

The lower or funnel part 11 is substantially of frusto-conical form having at its larger upper end a marginal upstanding flange 14 adapted to receive therein the rim 13 of the top part 10 for uniting the parts 10 and 11 of the attachment. The lower end of the funnel 11 is provided with a relatively large opening, and from its inner marginal edge depends a funnel neck 15, which latter may be reinforced by an interior band 16 carried therein at the lower end of the neck 15. A sleeve 17 may be fixed to part 11, but preferably frictionally engages over the neck 15 and abuts at its upper end against a ring 18 surrounding the base portion of the neck. The lower end of the sleeve 17 is closed by a bottom disk or plate 19 secured to the sleeve 17, and provided at its central portion with a relatively small through passage 20 covered by a strainer or screen 21 of the desired mesh.

A disk valve 22, which may be of circular form, is mounted at one edge upon a hinge 23 which is secured exteriorly to one side of the sleeve 17. The opposite edge of the disk 22 has a lip or projection 24 extending beyond the adjacent side of sleeve 17 when the valve 22 is in closed position against the lower face of the disk 19. The bottom 19 is also provided with a lip 25 projecting from one side of the sleeve 17, and which is adapted to overlie the lip 24. A hanger 26, preferably in the form of a length of wire, is secured to the sleeve 17 and terminates at its lower end in an eye which lies in an opening 27 formed through the lip 25. A weight 28 projects at its upper end into the opening 27 and is hingedly connected thereto at the eye of the hanger 26. The weight 28 is in the form of an elongated bar, and is suspended through a relatively large opening 29 formed through the lip 24 of the valve 22. The lip 24 is held in position about the weight 28, near the upper end thereof, by a spring finger 30. The finger 30

2
30 is of leaf spring form, and is seated in a longitudinal recess in the outer side of the weight 28. The upper end of the finger is sprung from the recess and may be bent laterally thereat to form a supporting shoulder adapted to engage the under side of the lip 24 and support the same and the valve 22 in partly raised position.

The major portion of the weight 28 extends below the valve 22, and when the receptacle A is tilted or upset, the weight 28 swings upon the hanger 26 in the direction in which the receptacle is tilted. This swinging of the weight 28 engages the latter 15 against the inner marginal edge of the lip 24 and forces the latter toward the lip 25, binding the disk valve 22 against the bottom 19 and completely closing the opening 20.

20 The upper end of the weight 28 is rounded so that the weight may swing in any direction to close the valve 22.

Lugs 31 are upturned from the opposite lateral edges of the disk 22 and bear against 25 the outer side of the sleeve 17 to brace the valve against lateral distortion by the weight. The valve 22 may be disengaged from the weight 28 by depressing the spring 30 of the latter to move the shoulder of the 30 spring into line with the opening 29 for passage therethrough, the lug 24 being adapted to be slid longitudinally over the weight.

The receptacle A is provided at opposite 35 sides with a pair of spring ears 32, secured by rivets or the like to the receptacle beneath the bead B. The ears 32 are struck inwardly intermediate their ends to form hooks or shoulders 33 adapted to engage 40 over the flange 10^a and hold it to the bead B. A bail or handle 34 is hinged upon the ears 32 to support the receptacle.

By springing the ears 32 outwardly the attachment may be removed from the receptacle A. The top part 10 may have an 45 upstanding flange 35 through which liquid may be poured, the liquid passing into the attachment and flowing through opening 20, past valve 22, and into the receptacle A.

50 It is within the scope of the invention to

make such changes and modifications as are within the scope of the following claims.

What I claim is:—

1. The combination with a receptacle, of a closure member fitting over the top of the receptacle and having an opening therethrough adapted to admit filling the receptacle, a valve hinged on said closure member for closing the opening, and a weight hinged at its upper end to said member in 60 spaced relation to the hinged connection thereof and depending through said valve, the weight being free to swing in all lateral directions upon the tilting of the receptacle to bear against the adjacent marginal edge 65 portion of the valve to close it.

2. The combination with a receptacle, of a closure member fitting over the top of the receptacle and having an opening therethrough adapted to admit filling the receptacle, a valve hinged on said closure member for closing the opening, a weight hinged at its upper end to said member and suspended therefrom through the valve, the weight having a shoulder spaced from its 75 upper end for engagement beneath the valve to support it in open position, said weight being free to swing when the receptacle is tilted to bind against the valve to close the same.

3. The combination with a receptacle, of a closure member mounted on the open end of the receptacle and provided with a filler opening therethrough, a disk valve hinged at one edge to the closure member, a weight 85 suspended from the closure member and passing through said disk valve, a spring arm mounted upon the weight and diverging from the upper end thereof to form a shoulder to support the valve in open position, said weight being free to swing upon the tilting of the receptacle to bind against the valve for closing the same.

In testimony whereof I affix my signature in presence of two witnesses.

WINFIELD CATLIN.

Witnesses:

EARL M. DOWD.

THOMAS O. PEACOCK.
